United States Patent

Des. 240,090
Patented May 25, 1976

240,090

PURSE

Milton I. Siegel, Scottsdale, Ariz., assignor to AMBA
Marketing Systems, Inc., Tempe, Ariz.

Filed June 20, 1975, Ser. No. 588,892

Term of patent 14 years

Int. Cl. D3—01

U.S. Cl. D87—3 F

FIG. 1

FIG. 2

FIG. 3

FIG. 1 is a perspective view of a purse showing my new design;

FIG. 2 is a bottom rear perspective view thereof, an intermediate portion of the strap being broken away and omitted for convenience of illustration; and

FIG. 3 is a top plan view thereof.

I claim:

The ornamental design for a purse, as shown and described.
